DESIGN FOR A CEMETERY MEMORIAL

Rudolph Baumgarth, Traverse City, Mich.

Application October 16, 1939, Serial No. 87,693

Term of patent 7 years

To all whom it may concern:

Be it known that I, Rudolph Baumgarth, a citizen of the United States and a resident of Traverse City, in the county of Grand Traverse and State of Michigan, have invented the new, original, and ornamental Design for a Cemetery Memorial, of which the following is a specification, reference is had to the accompanying drawing, forming part thereof, in which:

The broken line showings are merely illustrative in character.

I claim:

The ornamental design for a cemetery memorial, as shown and described.

RUDOLPH BAUMGARTH.
